UNITED STATES PATENT OFFICE.

HORACE W. HOOD, OF NASHUA, NEW HAMPSHIRE.

FASTENER FOR THE MEETING-RAILS OF SASHES.

SPECIFICATION forming part of Letters Patent No. 510,686, dated December 12, 1893.

Application filed December 5, 1892. Serial No. 454,189. (No model.)

To all whom it may concern:

Be it known that I, HORACE W. HOOD, of Nashua, in the county of Hillsborough and State of New Hampshire, have invented certain new and useful Improvements in Sash-Locks, of which the following is a specification.

My invention relates to that class of sash-locks which in addition to securing the sashes so that neither can be moved up and down, serves to draw the meeting rails of the sashes together.

It is the object of my invention to provide such improvements in sash locks as will simplify their construction, cheapen the cost of their manufacture, and at the same time render the said devices more efficient and ready of manipulation than heretofore.

To these ends my invention consists in the construction and combination of parts as hereinafter described and claimed.

Referring to the drawings, in which the same letters designate the same parts or features, as the case may be, wherever they occur, Figure 1—represents the different parts of the lock or fastener, each part being shown in perspective. Fig. 2—is a plan of the fastener, with the parts in their relative positions, together, and in an unlocked position. Fig. 3—is a similar view with the parts in the position which they occupy when the lever has been given a nearly one-quarter turn. Fig. 4—is a similar view with the parts in the position which they occupy when the lever has been given a full quarter turn. Fig. 5—is a similar view with the parts in the position which they occupy when the lever has been given a half turn and the parts are locked.

40 *a* is a stump plate having a hook *a'* of a usual form.

b is the base plate having a hole *b'* for the rivet or pin *e*. A slot *b²* is formed in the base plate and has a portion *b³* concentric with the hole *b'*, and a short radial portion *b⁴*, the end of which communicates with the part *b³* at an angle so as to form an inner incline or cam surface *b⁵* and an outer incline or cam surface *b⁶*.

50 *c* represents the swinging catch, having a hook *c'* and an elongated slot *c²* through which the pin *e* passes. Near the end of the slot *c²*,

toward the hook, are two pins *c³*, *c⁴*, the lower one *c⁴*, being adapted to enter the slot *b²* of the base plate. These two pins are located 55 opposite each other on the catch, and they are preferably formed by means of a single piece of wire secured in a hole in the catch so as to project from the opposite sides thereof.

d is a lever having a handle *d'* and the hole 60 *d²* for the pin or rivet *e*.

d³ is an eccentric slot extending one-quarter way around the hole *d²* and terminating at its outer end in a short radial slot, *d⁴*.

The parts being secured together in their 65 relative positions as shown, by the pin or rivet *e*, and applied to one of the sash rails of the window, and the stump plate being attached to the other sash rail, in the usual manner, the operation is as follows:—

When the parts are in the position shown in Fig. 2, and it is then desired to lock the sash rails and draw them together, the lever handle will be moved to the left and, owing to the pin *c³* being in the radial slot *d⁴* of the lever, the movement of the catch, with the lever, will be positive. When the pin *c⁴*, on the lower side of the catch strikes the outer incline or cam surface *b⁶* of the base plate, 75 the catch will be thereby, drawn slightly inward (see Fig. 3), and a further movement in the same direction, will cause the catch to be drawn inwardly to such an extent that the pin *c³* of the catch will be released from the radial slot *d⁴*. (See Fig. 4.) Further movement of the catch in a rotary direction, will be stopped, by the pin *c⁴* engaging the side of the short radial slot *b⁴* of the base plate, 80 while further movement of the lever in the same direction, will cause the eccentric slot *d³* of the latter, to act on the pin *c³* of the catch, and draw the latter inward so that its hook engages the hook *a'* of the stump plate 85 and draws the sash rails together. (See Fig. 5.) With the parts in this position, the catch *c* is firmly locked against lateral or swinging movement owing to its pin *c⁴* being at the inner end of the short radial slot *b⁴* of the base plate and prevented from movement by the sides of the said slot. The said catch is 90 thus locked against swinging movement by means entirely independent of the stump plate or its hook.

When the sash rails are to be unlocked, the

first quarter turn of the lever handle, outward and to the right, causes the eccentric slot d^3 of the lever, acting on the pin c^8 of the catch, to push the catch backward until the lower 5 pin c^4 of the catch is in position opposite the incline or cam surface b^5 of the base plate. A slight further movement of the lever in the same direction, causes the said pin to ride up the said incline and at the same time the pin 10 c^3 of the catch, moves outward into the radial slot d^4 of the lever and the lever and catch are thus locked together so that the latter is moved positively with the former during the completion of its movement back to 15 the position shown in Fig. 2.

Having now described my invention, what I claim is—

In a sash lock, the combination with a base plate having a slot consisting of a concentric part b^3 and the radial part b^4 , connected by 20 an inclined part forming cam surfaces b^5, b^6 ; a longitudinally slotted catch having pins projecting from its opposite sides, and a lever having the eccentric slot d^3 terminating at its outer end in a radial slot d^4 , substantially as described. 25

In testimony whereof I have signed my name to this specification, in the presence of two subscribing witnesses, this 25th day of November, A. D. 1892.

HORACE W. HOOD.
